UNITED STATES PATENT OFFICE.

GEORGE P. MACREADY, OF PROVIDENCE, RHODE ISLAND, ASSIGNOR TO FRANKLIN MACHINE COMPANY, OF PROVIDENCE, RHODE ISLAND, A CORPORATION OF RHODE ISLAND.

COLLAPSIBLE SPINDLE.

1,246,130.

Specification of Letters Patent.

Patented Nov. 13, 1917.

Application filed February 17, 1917. Serial No. 149,819.

To all whom it may concern:

Be it known that I, GEORGE P. MACREADY, a citizen of the United States, and resident of the city of Providence, in the county of Providence and State of Rhode Island, have invented certain new and useful Improvements in Collapsible Spindles, of which the following is a specification.

This invention relates to collapsible spindles onto which yarn, cord or other material is wound preferably in a ball form, and the object of this invention is to provide such a spindle with a plurality of flexible ribs, whereby the ribs may be bowed outwardly to form an expanded arbor and such expanded portion being adapted to be collapsed after the yarn has been wound thereon to facilitate the removal of the ball or bobbin therefrom.

20 A further object of this invention is to provide two collars on the arbor in which the opposite ends of each of the flexible ribs are pivotally mounted, one of said collars being adapted to slide on the arbor 25 to spring the ribs outwardly into bow form so that a ball of yarn may be formed thereon, and subsequently slide the collar back again and straighten the ribs to facilitate the removal of the ball.

30 A further object of the invention is to provide a simple and effective locking device for releasably retaining the collar when holding the ribs in expanded position.

The invention further consists in the provision of means in one or both of the collars for retaining the ribs in spaced apart relation.

With these and other objects in view the invention consists of certain novel features 40 of construction, as will be more fully described, and particularly pointed out in the appended claims.

In the accompanying drawings:

Figure 1— is a side elevation of my improved spindle showing the same in expanded position.

Fig. 2— is a sectional elevation showing the spindle in collapsed position.

Fig. 3— is a section on line 3—3 of Fig. 2 50 looking in the direction of the arrow and showing the arrangement of the ribs pivotally mounted in the collar about the center arbor.

Fig. 4— is a perspective view showing the

recessed portion of the collar in which the 55 ends of the ribs are mounted.

Fig. 5— is a diagrammatic view illustrating the general arrangement of the mechanism whereby the yarn is wound onto the spindle.

Fig. 6— is a side elevation showing the projections on the collar portion which serve to hold the ribs in spaced apart relation about the arbor.

Fig. 7— is a sectional elevation showing 65 the arrangement of the fingers which project between the ribs to hold them in spaced apart relation.

Fig. 8— is a side elevation showing one 70 end of the ribs pivotally mounted in the collar.

Fig. 9— is a perspective view showing one of the bendable ribs.

Referring to the drawings, 10 designates the arbor portion of my improved collapsible spindle which is shown in Fig. 5 as mounted in the frame 11 and provided with a worm gear 12 meshing with the worm 13 on the shaft 14, whereby the same is rotated. The outer end of this arbor is provided with 75 a collar 15 which is formed on a hub 16 whose head is notched as at 17 and on which is mounted a sleeve 18 forming an annular groove 39 between them, the whole being pinned as at 19 to the end of the arbor. A 80 plurality of flexible ribs 20 are mounted about this arbor 10, their opposite ends being each bent in the form of an eye as at 21 and 23 respectively, see Fig. 9, and these upper eyes are placed in this groove 39 and 85 a wire 22 is passed around the sleeve through these eyes thereby providing a hinge or pivot joint for each rib. The opposite or lower ends of these ribs are also similarly formed with eyes as at 23 and like their upper ends 90 are held in an annular groove 40 formed between the notched collar 24 on the hub 25 and the sleeve member 26. A wire 27 also passes through these eyes in the ends of the ribs binding them securely in this 100 groove, which wire also provides a hinge joint pintle on which these ends may swing. This outer sleeve 26 is secured to the hub 25 by means of the screw 28. The hub 25 is mounted to slide longitudinally on the 105 arbor 10 so that when it is moved upward or toward the fixed collar, the ribs 20 will bend outward in bow form as illustrated in

Fig. 1, to receive the yarn and when moved back to normal, as shown in Fig. 2, these ribs set straight or parallel with the arbor thus collapsing the spindle and permitting the ball which has been wound thereon, when in expanded position, to be readily removed therefrom.

In order to provide a simple and effective lock for retaining this collar in raised position, I have formed a spring wire 29, one end 30 of which is soldered in a corresponding groove 41 in the arbor, the free end 31 of the wire being adapted to normally spring outward when released and engage the shoulder 32 of this collar thereby retaining it against the closing pressure of the resilient ribs. When it is desired to release these ribs to straighten themselves out into normal position, it is only necessary to press this wire inward, in the position illustrated in Fig. 2 and the collar readily slides down over the same.

In order to facilitate the pressing inward of this wire lock, I have provided a separate and independent collar-shaped release member 33, which may be slid up over this wire thereby automatically drawing it inward to release the sliding collar 25. The stop member 34 is secured to the arbor to limit the upward movement of the sliding collar 25.

These resilient ribs may be formed of any suitable material but I preferably construct them of narrow strips of very thin spring steel so that they may be bowed readily into the desired shape.

The sleeves 18 and 26 may be provided with outwardly projecting fingers 35 on their edges, see Figs. 6, 7 and 8, so as to extend between the ribs at the joint to hold them in spaced apart relation.

One method of applying the yarn to this spindle when expanded is illustrated in Fig. 5, in which the spindle is rotated through the gears 12 and 13 and as rotated the yarn 36 is wound about it by means of a rapidly revolving flier 37 which is rotated through the shaft 38 to wind the yarn thereonto. The spindle while rotating also receives a continuous relative movement so as to lead the yarn in any desired form onto the spindle, the preferred form being the winding of the yarn into ball form and when this bobbin is completed it is only necessary to slide the release member 33 upward, trip the latch and permit the collar 25 to slide downward and collapse the spindle, thereby permitting the bobbin 44 as indicated in dotted line to be readily removed therefrom and the operation repeated.

I have described one illustrative embodiment of my invention, but I desire it to be understood that the specific terms employed are used in a generic and descriptive sense and not for the purpose of limitation, the scope of the invention being defined by the appended claims.

I claim:

1. A collapsible spindle comprising an arbor, a plurality of flexible ribs arranged about said arbor, means whereby the middle portion of said ribs may be bowed outward and returned when desired, and means whereby said ribs may be retained in bowed position. 70

2. A collapsible spindle comprising an arbor, a plurality of flexible ribs arranged about said arbor, a collar on the arbor in which each of the opposite ends of said ribs on the arbor are mounted, means whereby one of said collars may be moved 80 to bow the ribs outwardly, and means for releasably retaining said collar to hold the ribs in bowed position. 75

3. A collapsible spindle comprising an arbor, a plurality of flexible ribs arranged about said arbor, a collar on the arbor in which each of the opposite ends of said ribs are pivotally mounted, means whereby one of said collars may be moved toward the other to bend outward the middle portion of 90 said ribs into bow form, and means for releasably locking said collar in expanding position. 85

4. A collapsible spindle comprising a center arbor, a plurality of flexible ribs arranged about said arbor, a fixed collar at one end and a slideable collar at the other end of said ribs to which collars the ends of said ribs are pivotally mounted, means for spacing said ribs about said collars, a spring 100 lock for retaining the sliding collar when moved to expand said ribs, said lock being adapted to release said collar and permit it and the ribs to return to normal when desired. 95

5. A collapsible spindle comprising a center arbor, spring ribs arranged about said arbor, means for expanding the spindle by bending outward the middle portion of said ribs, means for rotating said spindle, means 110 for winding yarn onto the expanded portion of said spindle while rotating, and means for subsequently collapsing said expanded portion to facilitate the removal of the yarn wound thereon. 115

In testimony whereof I affix my signature in presence of a witness.

GEORGE P. MACREADY.

Witness:

HOWARD E. BARLOW.
